UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

DELIVERY APPARATUS FOR CONFECTIONERY MACHINES.

Application filed November 10, 1922. Serial No. 600,161.

To all whom it may concern:

Be it known that I, ALONZO LINTON BAUSMAN, a citizen of the United States, residing at Springfield, in the county of Hampden and State of Massachusetts, have invented new and useful Improvements in Delivery Apparatus for Confectionery Machines, of which the following is a specification.

This invention relates to delivery apparatus for confectionery machines and has particular reference to an apparatus designed to receive the candies from the machine, convey them through a cooling apparatus and thence to packing stations or any other point of delivery.

The apparatus is particularly applicable to a standard type of chocolate coating machine, receiving the freshly coated candies on a belt by means of which they are conveyed through a suitable cooling device and the coatings hardened, and affording means for loosening the hardened candies from such belt and conveying them past operators who pick up the candies and pack them or, if desired, delivering the candies into trays to be otherwise and later packed.

The object of the invention is to provide an apparatus of the class described embodying certain advantageous arrangements of parts and improved constructional features, as will more particularly appear in the following description and in the illustrative embodiment of the invention in the accompanying drawings, in which—

35 Figs. 1^a, 1^b, 1^c, and 1^d, taken together end to end show a complete plan view of the apparatus, certain parts of this view being shown in section;

40 Figs. 2^a, 2^b, 2^c, and 2^d, taken together end to end show a complete side elevational view of the apparatus,—certain parts of this view being also shown in section; and

45 Fig. 3 is a cross-sectional view taken on the line 3—3 of Fig. 1^b.

45 Referring to these drawings in detail, A represents a portion of the casing of any suitable candy making machine and this machine may, for example, be a candy coating machine of the general type disclosed in U. S. Letters Patent No. 790,184 granted May 16, 1905, on an invention of Gabriel Carlson. The product of this machine, such as candies coated with chocolate, are car-

ried on the usual conveyer *c* and by it transferred automatically to a conveyer 10. 55 The latter is usually an endless belt of suitable fabric and may have a special smooth glossy finish to prevent the candies from adhering too tightly thereto or a second belt, such as 11, of material, such as oil cloth or the like, may be associated with it, as illustrated. In any event, the conveyer, whether a single or double one, carries the candies, preferably in continuous fashion, through a casing B, wherein the coatings are cooled, as by currents of cold air which are caused to circulate therein. The cooled candies emerging from casing B are then stripped from the conveyer by a thin stripper plate 12 and slide down the latter upon a second 60 conveyer 13, which may be an ordinary canvas belt. Conveyer 13 is mounted to travel in a frame C and between two packing shelves 14 thereon and carries the finished candies within easy reach of the packers who remove them and pack them in boxes on shelves 14. Or, if it is not desired to thus pack the candies, the conveyer 13 is arranged to deliver them into trays *t*, 65 which are caused to move from below the conveyer past a chute 15, down which the candies fall into trays *t*.

70 The casing B, otherwise known as a cold box, will first be described. It consists of a relatively long box-like structure, having 75 openings 16 at opposite ends to receive the belts 10 and 11 and has a longitudinal partition 17 which divides it horizontally into upper and lower compartments 18 and 19, the former accommodating belts 10 and 11 80 in both upper and lower laps of travel and the lower containing the cooling means. Centrally arranged in casing B and disposed on opposite sides thereof are vertical 85 conduits 20 by means of which communication is established between the compartments 18 and 19. At each end of the casing similar conduits 21 are provided for the same 90 purpose. The lower compartment 19 is divided centrally by a vertical partition 22, 95 which extends in a general diagonal direction from one side wall of one conduit 20 to the opposite side wall of the other conduit so that one conduit 20 communicates with one half of compartment 19 and the other conduit 20 with the other half of the 100 105

compartment. The upper compartment 18 is similarly divided by two partitions 23 and 24, which are vertically spaced from one another to permit the passage of the 5 upper lap of belts 10 and 11 and the lower partition 24 is spaced from the partition 17 to permit the passage of the lower lap of belts 10 and 11.

Two fans 25, one for each conduit 20, are 10 disposed at the intersection of these conduits with the lower compartment 19, these two fans being mounted so that the thrust of one is balanced by the thrust of the other and both fans being fixed to a shaft 26 rotatably 15 mounted in and extending transversely across casing B. Cooling coils 27 are provided in each section of compartment 19, in which coils a suitable cooling medium, such as brine or ammonia, may be circulated. A 20 drip pan 28 is provided in underlying relation with the coils. Each fan draws air from the remote end of one compartment 18 through the two vertical conduits 21 into the compartment 19, which is located therebelow 25 and forces this air up through one of the central vertical conduits 20 and back into the same compartment 19. The air drawn back from compartment 18 travels along the coils 27 and is cooled to the desired degree. Baffles 29 are provided in each section of compartment 19 as best shown in 30 Figs. 1^b and 3, to cause the air to travel in a sinuous path, the better to effect its cooling. Each baffle 29 is fastened to a side 35 wall of casing B and is notched, as at 30, to slip over one side of coils 29 and projects into close proximity to the other side of these coils.

The casing B is preferably provided with 40 double walls, comprising outer and inner walls 31 and 32, which are spaced apart as shown in Fig. 3 and may receive between them suitable insulating material, indicated at 33. The cover for casing B is preferably made in a similar fashion and consists of a plurality of removable sections 34, whereby access may be had to the interior substantially from end to end thereof to permit assembly of parts therein.

50 The upper laps of belts 10 and 11 are supported during their travel through casing B upon a horizontally disposed table, which extends longitudinally of the casing and midway between the upper and lower walls of compartment 18. This table is made up of a plurality of thin sheet metal sections 35, which are mounted end to end in abutting relation and which have their abutting ends downturned, as at 36 (Fig. 2^b), in order 55 to eliminate sharp edges, such as might abrade belt 10. These sections 35 are supported by and between two laterally spaced angle irons 37, which extend longitudinally of the casing in parallel, but preferably 60 slightly spaced, relation with the side walls

thereof,—the angle irons 37 being supported at suitable intervals by brackets 38, thus leaving openings, as 39, through which communication may be established between the upper and lower portions of compartment 70 18. Each section 35 is perforated, as at 39', to allow the cold air to pass therethrough from below and reach the under lap of belt 10, the better and more rapidly to cool the bottoms of the confections. 75

In assembling the parts in casing B, all the work is done from the top,—the cover sections 34 being removed. The drip pan 28 is first laid in place, after which the coils 27 are inserted. Then the baffles 29 are mounted 80 in place, together with partition 22 and the fans,—after which partition 17 is laid in. Then belt 10, or belts 10 and 11, if both are to be used, is laid upon partition 17 and the sections 35 are inserted one by one between 85 the laps of the belt. The sections are then lifted one by one diagonally between angle irons 37, to a position above the latter after which they are positioned horizontally and deposited on the angle irons as shown. 90 This work is done either before the belts are mounted on their end supports or else while sufficient slack is otherwise provided for this purpose. The various parts in casing B are mounted in such a fashion as to be 95 conveniently removable to permit assembly in the manner described. The covers 34, as heretofore described, are also conveniently removable for the same purpose and also for the purpose of gaining access to the 100 confections when necessary or desired.

The conveyers 10 and 11 are supported at one end by a table 40 (Fig. 2^d) which is pivotally supported at 41 at one end from the casing B and at the other end rests 105 upon a shelf s of the coating machine A, preferably being adjustably supported from such shelf through the intermediary of screws 42. The described arrangement enables the receiving end of conveyers 10 and 11 to be conveniently aligned with the delivery end of conveyer c. The table 40 has a comparatively thin rounded edge around which the conveyers 10 and 11 move 110 in passing from their lower to their upper laps of travel. Referring now to Fig. 2^a, the other end of conveyer 10 passes around a driving roll 44 which is rotatably mounted in a floor stand D. A small roll 45, also rotatably supported in the latter, is provided to cause the conveyer to turn a more nearly square corner than it otherwise would at the end of its upper lap of travel. If two belts are used, the belt 11 only need 115 travel over roll 45. From roll 44, both belts travel over an idler roll 46 and thence to a second idler 47 (Fig. 2^b). Belt 10 extends downwardly around a roll 48, thence upwardly over a roll 47' and thence along the partition 17. Belt 11 also extends from roll 120 125 130

46 to roll 47 and thence downwardly around a separate roll 49 and then upwardly over roll 47', returning along the same path as belt 10. The rolls 48 and 49 constitute 5 separate belt tensioning devices for the belts 10 and 11, respectively, these rolls being suitably mounted, as indicated, for movement in a general vertical direction and functioning, as by their weight, to keep the 10 belts tight. Referring to Fig. 2^a, the roll 44 carries a worm gear 50 which is driven by a worm 51 fixed on a shaft 52, rotatably mounted in suitable bearings on a side wall of floor stand D. Shaft 52 is connected by 15 a universal joint 53 to a shaft 54 which extends, as indicated, back to the coating machine A, being connected by a universal joint 55 to that shaft x of such machine which usually drives the ordinary confection delivery apparatus. The shaft 54 includes a suitable number of universal joints, as indicated, and is mainly supported by 20 bearings provided on the casing B.

The conveyer 13 is driven from a roll 56 25 mounted in floor stand D and this roll carries a worm 57 which is driven from a worm gear 58 fixed on a shaft 59, rotatably mounted in suitable bearings on one side wall of the floor stand, but below the described shaft 52. The shafts 52 and 59 are connected by any suitable speed changing device so that conveyer 13 may be driven from conveyer 10 but at various relative speeds. Thus, shaft 52 may carry a group 30 of three gears 60, which are slidable on the shaft by means of a shift lever 61. Shaft 59 carries three axially spaced gears 62 of complementary sizes. As shown, the middle gear 60 is in mesh with the middle gear 62, whereby conveyer 13 is driven faster than conveyer 10, but the gears 60 may be shifted to the right to cause the right hand gears 60 and 62 to engage and thereby drive conveyer 13 at slower speed than conveyer 45 10 or the gears 62 may be shifted to the left to cause the left hand gears 60 and 62 to engage and thereby drive conveyer 13 at the same speed as conveyer 10. Thus, by this speed changing device, the confections may 50 have the same spacing on conveyer 13 as a conveyer 10, or the spacing may be made greater or less, as desired.

The conveyer 13 is supported during its 55 upper lap of travel on a table 64, carrying at one end an idler roll 65 over which the conveyer passes and returns to an idler roll 66, thence passing downwardly to tension roll 67 and thence upwardly to a roll 68, from which it returns to driving roll 56. A roll 69 is provided to cause the conveyer 60 65 to make a comparatively sharp turn in passing to its upper lap of travel. Roll 69 is located adjacent but below roll 44, and the inclined stripper plate 12 bridges the gap 65 between the two conveyers and has an edge

lying in close proximity to conveyer 11 as it passes over roll 44. Plate 12 is stationarily supported from the side walls of floor stand D, as indicated. The table 64 has longitudinally disposed angle irons 70 secured to its side edges, which upstand from the table and furnish side guides for conveyer 13. That end of table 64 remote from roll 65 carries two laterally spaced arms 71 which are pivoted at 72 to the floor stand D. The table 64 is otherwise supported by the angle irons 70 resting on brackets 73 fixed to frame C. Thus, table 64 may be lifted, if necessary, to gain access to parts below and it is susceptible to a rising movement without damage should this prove necessary. 75 80

The packing shelves 14 are provided with backs 75, between which the table 64 and conveyer 13 is arranged. These backs 75 have openings 76 therein near the delivery 85 end of conveyer 13 and below table 64, through which a tray t may be passed and disposed in under the table 64 and conveyer 13. The tray, thus positioned, is supported on two of a series of three rolls 90 77. The center roll of this series is driven by worm gearing 78 from a shaft 79 which is connected to the described shaft 59, whereby it is driven at approximately the same speed as conveyer 13. Thus the tray t, positioned as described, is moved in the same direction as conveyer 13 and passed outwardly beneath the chute 15 to receive the candies delivered upon the latter by the conveyer. The chute 15 is pivotally supported to swing 95 about an axis concentric with that of roll 65 and can rise and fall to accommodate the outwardly moving tray. The latter eventually engages the outer roll 77 of the series, which roll is driven by a chain 80 and suitable sprockets from the middle roll of the series. The tray is eventually moved upon idler rolls 81 where it rests until removed by an operator. The rolls 77 and 81 are suitably mounted in bearings provided on the 100 backs 75. 105

The operation of the apparatus will sufficiently appear from the foregoing description.

The invention has been disclosed herein, 115 in an embodiment at present preferred, for illustrative purposes, but the scope of the invention is defined by the appended claims rather than by the foregoing description.

What I claim is:

1. In combination, a frame having laterally spaced upright side walls, a table disposed between said walls and pivotally supported at one end, means carried by said frame for supporting the other end of said table in a manner such that the latter may be swung upwardly on its pivotal support when desired, a belt travelling over said table from the first named to the last named end and returning closely adjacent the lower face 120 125 130

thereof, and a second conveying means having a part located beneath said table and accessible by swinging the table upwardly.

2. In combination, a frame having a pair of laterally upright side walls with packing shelves on the outer faces thereof, a pedestal adjacent one end of said frame, a table pivotally connected at one end to said pedestal, belt driving and guiding rolls mounted in said pedestal, a belt driven and guided by said rolls and extending over the upper face of said table passing from the first named end to the opposite end, thence around the last named end and returning along the lower face of the table, and a second conveying means having a part located beneath said table and accessible when the latter is swung upwardly.

3. In combination, a frame having a pair of laterally upright side walls with packing shelves on the outer faces thereof, a pedestal adjacent one end of said frame, a table pivotally connected at one end to said pedestal, belt driving and guiding rolls mounted in said pedestal, a belt driven and guided by said rolls and extending over the upper face of said table passing from the first named end to the opposite end, thence around the last named end and returning along the lower face of the table, belt tensioning means arranged to permit upward swinging movement of the table without interruption of the travel of said belt, and a second conveying means having a part located beneath said table and accessible when the latter is swung upwardly.

4. In combination, a frame having a pair of laterally upright side walls with packing shelves on the outer faces thereof, a pedestal adjacent one end of said frame, a table pivotally connected at one end to said pedestal, belt driving and guiding rolls mounted in said pedestal, a belt driven and guided by said rolls and extending over the upper face of said table passing from the first named end to the opposite end, thence around the last named end and returning along the lower face of the table, a guide roll and a vertically movable roll both mounted in said frame, said belt in its return travel passing over said guide roll and downwardly to and around the vertically movable roll and then upwardly to one of the guiding rolls in said pedestal.

5. In combination, a cooling apparatus, a conveyer to carry confections therethrough, a packing table, a conveyer to carry cooled confections into accessible relation with the packing table, a frame and a supporting pedestal therefor disposed between said apparatus and table, a driving roll for each conveyer mounted in adjacent relation in said frame, guiding means in said frame to direct the delivery end of the first conveyer into adjacent relation with the receiving end of the first conveyer, and common driving means for both said rolls including speed changing devices to vary the speed of one with relation to the other.

6. In combination, a cooling apparatus, a conveyer to carry confections therethrough, a packing table, a conveyer to carry cooled confections into accessible relation with the packing table, a frame and a supporting pedestal therefor disposed between said apparatus and table, a driving roll for each conveyer mounted in adjacent relation in said frame, guiding means in said frame to direct the delivery end of the first conveyer into adjacent relation with but at a somewhat higher level than the receiving end of the first conveyer, common driving means for both said rolls including speed changing devices to vary the speed of one with relation to the other, and an inclined stripping plate fixed in said frame and connecting the delivery end of the first conveyer to the receiving end of the second conveyer.

7. Delivery apparatus for a confectionery machine, comprising, conveying means including an endless belt to receive and transport the products of said machine, a frame having spaced side walls between which said belt is arranged to travel, a table underlying and supporting the upper lap of said belt near its delivery end, said belt passing around one end of said table and returning closely adjacent the lower face of the latter, means pivotally supporting the other end of said table, means carried by said side walls to support the table against swinging movement in one direction, and a tray conveyer having a part located beneath said belt and accessible by swinging said table in the other direction.

In testimony whereof I have affixed my signature.

ALONZO LINTON BAUSMAN.
